United States Patent Office

Des. 197,497
Patented Feb. 11, 1964

197,497

STORE FIXTURE

William Heidemann, 5231 Veronica St.,
Los Angeles, Calif.

Filed Jan. 25, 1963, Ser. No. 73,319

Term of patent 14 years

(Cl. D80—2)

FIG. 1.

FIG. 3.

FIG. 2.

FIG. 4.

FIG. 5.

FIG. 6.

FIG. 1 is a front elevational view of a store fixture showing my new design;

FIG. 2 is a top plan view thereof;

FIG. 3 is a left side elevational view thereof;

FIG. 4 is a rear elevational view thereof;

FIG. 5 is a right side elevational view thereof; and

FIG. 6 is a bottom plan view thereof.

I claim:

The ornamental design for a store fixture, as shown.
